UNITED STATES PATENT OFFICE

121,563

DESIGN FOR SUNGLASSES OR SIMILAR ARTICLE

Albert M. Bressler, New York, N. Y.

Application May 28, 1940, Serial No. 92,662

Term of patent 3½ years

To all whom it may concern:

Be it known that I, Albert M. Bressler, a citizen of the United States, residing in New York city, in the county of New York, and in the State of New York, have invented a new, original, and ornamental Design for Sunglasses or Similar Article, of which the following is a specification, reference being had to the accompanying drawing, forming part thereof,

I claim:

The ornamental design for sunglasses or similar article, substantially as shown.

ALBERT M. BRESSLER.
